UNITED STATES PATENT OFFICE

2,593,551

FUEL INJECTION PUMP

Nicholas Fodor, Wilmette, Ill.

Application December 8, 1947, Serial No. 790,277

5 Claims. (Cl. 103—41)

1

This invention has to do with fuel injection pumps and is particularly concerned with an improved pump of the type in which the quantity of fuel delivered by the pump during each injection is controlled at the inlet of the pump. Although capable of being used for other purposes the new pump is particularly well suited for use in connection with Diesel engines.

The principal object of the invention is to provide an improved pump of the character described having simple yet effective means for bypassing excess fuel back into the fuel supply chamber of the pump without creating objectionable turbulence therein.

Other objects and advantages of the invention will be apparent to those skilled in the art upon a full understanding of the construction, arrangement and operation of the parts entering into the construction of the improved pump.

A preferred embodiment of the invention is presented herein for the purpose of exemplification but it will of course be appreciated that the invention is susceptible of incorporation in other structurally modified forms coming equally within the scope of the appended claims.

In the accompanying drawings:

Fig. 1 is a side view of a fuel injection pump which has incorporated therein the improvement constituting the present invention;

Fig. 2 is a different side view of the pump;

Fig. 3 is a plan view of the pump;

Fig. 4 is a vertical section through the pump, taken on approximately the line 4—4 of Fig. 1;

Fig. 5 is another vertical section, taken on approximately the line 5—5 of Fig. 2; and

Fig. 6 is a horizontal section, taken on approximately the line 6—6 of Fig. 4.

Referring in more detail to the drawings, it will be observed that the pump is characterized by a body 10 which is adapted to be bolted or otherwise securely fastened to the associated engine. The body 10 is provided with a vertical bore 11 and horizontal bore 12. The upper central portion of the bore 11 constitutes the pumping chamber, while the bore 12 constitutes the fuel inlet chamber.

A plunger 13 reciprocates vertically with a constant length stroke within the bore 11 in freely slideable but fluid-tight engagement with the same. The plunger 13 is moved upwardly by a cam 14 on the cam shaft 15 of the associated engine and is moved downwardly by a coil spring 16 which is compressed between the underside of the body 10 and a spring seat 17 secured to the lower exposed end 18 of the plunger.

The plunger 13 is provided a predetermined

2

distance below its upper end with an annular groove 19, and the groove 19 is connected to the pumping chamber space above the plunger by radial passages 20 in the bottom of the groove which communicate with a centrally arranged upwardly opening bore 21 in the upper end of the plunger.

The upper end of the bore 11 is closed off by a delivery valve assembly 22, which assembly includes a delivery union 23 which is adapted to be connected by suitable tubing with the injector, an annular valve seat 24 at the lower end of the union, a vertically movable valve 25 on the seat, and a small coil spring 26 for pressing the valve downwardly against the seat.

The bore 12, which constitutes the fuel supply chamber, is adapted to be connected at one end with the fuel supply line 27 and is adapted to be closed at its other end by a screw plug 28, either end of the bore 12 being optionally connectable with the fuel supply line.

A fuel quantity control shaft 29 is rotatably mounted in a horizontal position in the body 10, with its center portion 30 passing crosswise through and exposed within the bore 12, and with its end portions 31 and 32 journaled respectively in aligned bores 33 and 34 in freely rotatable but fluid-tight engagement with the latter. One end of the shaft 29 projects from the body 10 and is provided with a lever 35 by means of which the shaft is adapted to be turned through a predetermined angle.

The portion 30 of the shaft 29 which is exposed within the bore 12 is provided with radial passages 36 which open into a longitudinal extending bore 37 in the shaft. The bore 37 is closed at its far end by a screw plug 38 and is connected with a radial passage 39 which opens into an eccentrically formed arcuate groove 40 in the outer surface of the shaft. The groove 40 is formed in that portion of the shaft 29 which is journaled within the bore 34, and is located at a point directly opposite the bore 11. The bore 34 is connected with the bore 11 at the location of the groove 40 by an inlet port 41, which port opens into the pumping chamber portion of the bore 11 just above the edge of the top 42 of the plunger 13 when the latter is in its lowermost position.

Below the inlet port 41 the bore 11 connects again with the bore 12 by a spill port 43, which port is adapted to communicate with the annular groove 19 in the plunger 13 at a predetermined point in the upward travel of the plunger, whereby to by-pass fuel back into the bore 12.

The improvement which constitutes the pres-

ent invention is the provision in the bore 12 of a special spill deflecting element 44, which element may advantageously consist of a pin 45 which is press fitted or otherwise securely held within a bore 46 in the body 10 with its axis aligned with the spill port 43 and with its confronting end 47 abruptly formed at right angles to the axis of the spill port. The pin 45 is preferably somewhat larger in diameter than the spill port 43 and is located in direct opposition and in close proximity to the latter. The pin is preferably spaced about $\frac{3}{2}$ of an inch from the discharge end of the spill port, but this spacing may be increased or decreased and yet afford the desired baffling effect on the fuel.

The pump operates as follows: In the lowermost position of the plunger 13 (which is the position shown in Figs. 4 and 5) fuel from the bore 12 flows through the inlet port 41 into the bore 11 across the top 42 of the plunger, metered by the restriction determined by the angular position of the fuel quantity control shaft 29. As the plunger 13 moves upwardly in the bore 11 the top 42 of the plunger cuts off the inlet port 41, after which the fuel trapped in the bore 11 above the plunger is forced upwardly past the delivery valve 25 and through the tube leading to the injector. As soon as the plunger 13 in its upward movement reaches a position wherein the groove 19 uncovers the spill port 43 delivery of fuel through the valve 35 abruptly ceases and that fuel which is displaced by the movement of the plunger during the remainder of its upward movement is by-passed through the spill port 43 back into the bore 12.

As the fuel is discharged from the spill port 43 back into the bore 12 it impinges squarely against the plug-like end 47 of the baffling element 44 immediately upon entering the bore and has its dynamic energy quickly and effectively dissipated. This dissipation, by the means herein disclosed, has been found to materially improve the operation of a pump of this type, preventing pressure waves in the fuel from penetrating into the bore 12 to such extent as to cause therein unwanted momentary increases in the pressure and violent motion of the fuel.

I claim:

1. In a fuel injection pump, a pumping chamber, a constant stroke plunger reciprocally mounted therein, said plunger having a circumferentially continuous head which closely fits the pumping chamber and terminates at its lower end in a laterally opening recess, which recess communicates through the head with an upwardly opening recess in the top of the latter, an outlet port from the upper end of the pumping chamber adapted for connection with an injector, a fuel chamber for both supplying fuel to the pumping chamber and receiving excess fuel from that chamber, a single inlet port into the pumping chamber from the fuel chamber, which port is located just above the top of the head of the plunger in the lowermost position of the latter, an adjustable metering valve located between the fuel chamber and the inlet port for variably controlling the rate of flow

of the fuel from the fuel chamber through said inlet port into the pumping chamber, a single spill port from the pumping chamber into the fuel chamber, which port is located a substantial distance below the inlet port and is closed off from the pumping chamber by the head of the plunger in the lowermost position of the plunger, being placed in communication with the pumping chamber by said laterally opening recess only after the piston has moved upwardly a predetermined distance, and a baffle member located in the fuel chamber adjacent to but spaced from the discharge end of the spill port, in a position in direct opposition thereto, for reducing in the fuel present in the fuel chamber the turbulence which would otherwise be caused by the fuel returned to the fuel chamber through the spill port, without obstructing such return.

2. A fuel injection pump of the construction set forth in claim 1, wherein the baffle member is so arranged as to afford a substantially flat right angular impingement surface for the fuel entering the fuel chamber from the spill port.

3. A fuel injection pump of the construction set forth in claim 1, wherein the baffle member is structurally separate from the fuel chamber and is capable of being adjusted toward or away from the discharge end of the spill port.

4. A fuel injection pump of the construction set forth in claim 1, wherein the baffle member consists of a pin which is secured in a bore in the fuel chamber in substantially axial registration with the spill port and terminates in a substantially flat end face, which end face is spaced but a small fraction of its diameter from the end of the spill port.

5. A fuel injection pump of the construction set forth in claim 1, wherein the fuel chamber consists of a short bore in right angular laterally spaced relation to the pumping chamber, the adjustable metering valve includes a rotatable operating stem which extends crosswise through said bore and is provided with a longitudinally extending fuel passage which opens radially at one end into communication with said bore and at the other end into communication with the fuel chamber, and the baffle member consists of a pin which extends crosswise of said bore in closely spaced relation to said stem and in substantially axial registration with the spill port and terminates in an end face which is spaced but a small fraction of its diameter from the end of the spill port.
